DRILLING APPARATUS

Michael D. Carleton, Houston, Tex., assignor to
 Reed Roller Bit Company, Houston, Tex., a
 corporation of Texas

Application May 18, 1940, Serial No. 335,880

3 Claims. (CL 255—71)

This invention relates to cross roller bits and particularly to the bearings for the side cutters thereof.

In the mounting of side cutters for cross roller bits provision must be made for taking the multitude of very great stresses placed upon the side cutters during the operation of a cross roller bit. Although these stresses are very great, they may all be resolved into radial loads and end thrusts.

It is an object of this invention to provide a bearing for a side cutter which can be easily and cheaply manufactured and yet which will be capable of taking both the radial loads and end thrusts to which the cutters are subjected.

Another object of this invention is to provide such a structure which may be easily and quickly assembled and which will not be susceptible of becoming disassembled in use.

Other objects and advantages of this invention will become apparent from the following description taken in connection with the accompanying drawing.

In the drawing a single figure illustrates a side-view partly in vertical cross section of a cross roller bit having bearings for its side cutters constructed in accordance with this invention.

In this instance, the bit consists of a shank 1 having threads 2 thereon and having legs 3 and 4 suitably secured to its lower end. A suitable plate 5 having slush openings 6 therein is provided for directing the slush against the teeth of the respective cutters. Each of the legs 4 is adapted to provide a support for one outer end of a cross cutter shaft 7 on which are rotatably mounted cross roller cutters 8.

The legs 3 are made separate from each other and each is provided with a downwardly and inwardly extending opening adapted to receive a shaft-like end portion 10 on one of the opposite ends of the bridge 11. The bridge 11, as illustrated, embraces and serves as a support for the central portion of the cross cutter shaft 7 and adjacent its outer ends is formed with two ball bearing races 12 and 13. The side cutters 14 are provided with corresponding ball races, and within these respective ball races there are placed two rows of balls 15 and 16 for rotatably supporting each side cutter.

In the form illustrated the legs 3 are formed separate from each other and from the shank 1 and are welded to the shank as shown at 11.

In assembling the bit just described the balls 15 are first put in place within the races 12 on the bridge. The side cutters 14 are then placed over the ends of the bridge and against the balls 16.

15. Next the balls 16 are put in place within the outer ends of the side cutters and the ends 10 of the bridge are inserted into the openings in the legs 3 of the bit. The legs 3 are then welded in place and the ends 10 are welded in the legs 3 as shown at 18.

It will be appreciated that in the construction just described the two sets of balls 15 and 16 within the respective side cutters will tend to support these side cutters against radial loads and end thrusts and will very effectively tend to prevent the side cutters from tilting with respect to their axes or from running in or running out with respect to the axis of the bit during the operation thereof.

It will further be seen that the device will be relatively simple to construct and rugged and durable in operation.

Having described my invention, I claim:

1. In a roller bit, a shank having side cutter legs extending downwardly therefrom, a bridge extending between said legs and having end portions supported by said legs, a pair of side cutters surrounding the end portion of said bridge adjacent said legs, each end of said bridge having an inner ball race adapted to receive balls for taking end thrusts in either direction and an outer ball race adapted to receive balls for taking end thrusts in an inward direction, each of said legs having a ball race adapted to complement said last mentioned ball races on the bridge for taking end thrust in an outward direction, each of said side cutters having a pair of ball races corresponding to the ball races on said bridge and lying adjacent the opposite ends of said side cutters respectively, and balls in said ball races.

2. In a roller bit, a shank having downwardly extending cutter legs thereon, a bridge extending between said legs and having its opposite ends engaged and supported by said legs, the opposite end portions of said bridge inwardly of said legs providing bearings, a pair of side cutters on said bearings, a pair of outwardly facing flanges on said bridge adjacent the inner end portions of said bearings providing outwardly facing ball races for taking inward thrust, the inner surfaces of each of said legs being provided with inwardly facing ball races adapted to take outward thrust, the bearing portions of said bridge having ball races complementary to said end thrust receiving races respectively, and each of said cutters having a pair of ball races facing towards the opposite ends of said cutters respectively, and balls in said ball races for taking the thrust and radial loads from said cutters.

3. In a roller bit, a shank having downwardly extending cutter legs thereon, a bridge extending between said legs and having its opposite ends engaged and supported by said legs, the opposite end portions of said bridge inwardly of said legs providing bearings, a pair of side cutters on said bearings, a pair of outwardly facing flanges on said bridge adjacent the inner end portions of said bearings providing outwardly facing ball races for taking inward thrust from said side cutters, the inner surface of each of said legs being

5 provided with inwardly facing ball races adapted to take outward thrust from said side cutters, the bearing portions of said bridge having radial ball races complementary to said end thrust receiving races respectively, and each of said cutters having a pair of ball races facing radially inwardly and toward the opposite ends of said cutters respectively, and balls in said ball races for taking the thrusts and radial loads from said cutters.

10

MICHAEL D. CARLETON.
